[57] CLAIM

The ornamental design for an electrocutor for flying insects, substantially as shown and described.

DESCRIPTION

FIG. 1 is a side elevational view of the electrocutor for flying insects, the opposite side elevation thereof being opposite-hand;

FIG. 2 is a top plan view of FIG. 1;

FIG. 3 is a plan view looking at the bottom of FIG. 1;

FIG. 4 is an elevational view of the left-hand end of FIG. 1;

FIG. 5 is an elevational view of the right-hand end of FIG. 1;

FIG. 6 is a longitudinal sectional view taken along line 6—6 in FIG. 2;

FIG. 7 is a sectional plan view taken along lines 7—7 in FIGS. 1 and 6, and

FIG. 8 is an enlarged cross-sectional view taken along lines 8—8 in FIGS. 1 and 6.
